ELECTRIC SWITCH

Filed Jan. 19, 1931

UNITED STATES PATENT OFFICE

HENRY P. PINKHAM, OF WOLLASTON, MASSACHUSETTS, ASSIGNOR TO CONDIT ELECTRICAL MANUFACTURING CORPORATION, OF HYDE PARK, MASSACHUSETTS, A CORPORATION OF MASSACHUSETTS

ELECTRIC SWITCH

Application filed January 19, 1931. Serial No. 509,718.

This invention relates to safety enclosed electric switches especially adapted for the control of small power circuits, as motor circuits, and the like.

5 Switches of this type are usually electrical-
ly operated with push button control for
closing and opening the switch to start and
stop the motor and the control push buttons
may be located at a considerable distance
10 from the switch which they control. It is
therefore desirable to provide some means
for completely isolating the motor control
switch from the power supply when it is nec-
essary to make repairs on the switch or the
15 load circuits controlled thereby.

It is an object of this invention to provide
an improved arrangement of motor circuit
switch by which the motor control switch
20 can be completely disconnected from the
power line, whereby repairs to the control
switch or to the motor and the apparatus
driven thereby can be made with safety.

It is a further object of the invention to
25 provide the electrically operated control
switch with a manually operated disconnecting
switch in series therewith, with both as
a unitary apparatus in a single enclosing cas-
ing; and to provide improved means for in-
30 terlocking the casing cover with the operat-
ing mechanism of the disconnecting switch,
whereby the cover remains locked until the
disconnecting switch has been opened and
whereby the disconnecting switch cannot be
35 closed until the cover has been closed.

A further object is to provide an enclos-
ing casing for a main switch and a discon-
necting switch as above described having
40 simple means for locking the disconnecting
switch in either open or closed position.

A still further object of the invention is
45 to provide locking means which is connected
with the switch operating mechanism of the
disconnecting switch and is operative posi-
tively both into and out of locking position
by the closing and opening movements of
50 said mechanism, thus preventing failure of
the interlock by sticking of the locking
mechanism.

50 A yet further object is generally to im-

prove switches for the control of small power
circuits.

Fig. 1 is a side elevation of the circuit con-
trolling and disconnecting switches embody-
ing the invention.

55

Fig. 2 is a front elevation of the operating
mechanism of the disconnecting switch of
Fig. 1, the cover being partly broken away.

Fig. 3 is a sectional detail of the operating
mechanism of Fig. 2.

60

Fig. 4 is a detailed showing of the inter-
lock between the casing cover and the oper-
ating mechanism for the disconnecting
switch, the parts being shown in switch
65 closed position.

65

Fig. 5 is a detail of the interlocking mech-
anism in switch open position with the cover
open.

Fig. 6 is a perspective view of the locking
plate.

70

Fig. 7 is a detail of the switch operating
handle.

As herein shown the switching apparatus
embodimenting the invention includes an elec-
trically operated circuit interrupter or
switch A, which is adapted to be remote con-
trolled, and a manually operable motor cir-
cuit disconnecting switch B, which is adapted
75 to be connected between the interrupter A
and the power source, whereby to completely
electrically isolate the motor circuit and the
interrupter when the switch is opened. Said
switches are contained in a common enclos-
ing casing having complementary front and
80 back casing sections 10 and 12 respectively,
the front section 10 of which is hinged at one
side to said back section and constitutes a re-
movable closure for the open front of said
back section whereby to permit access to both
85 switches when the casing is open. As here
shown the casing preferably is relatively tall
and narrow and the switches A and B are lo-
cated one above the other therein.

The invention is particularly concerned
90 with an improved interlocking means which
governs the operation of the manually con-
trolled operating mechanism of the discon-
necting switch and the opening of the cover
10 and prevents the improper operation of
either relative to the other. The interlocking
100

means is also so arranged that access to the interrupter cannot be gained while it is under potential.

Said disconnecting switch B is supported 5 on an L-shaped supporting plate or bracket 14 which includes a back plate 16 which is secured removably by means of key hole slots 16a and screws 17 onto the inner face of the rear wall 12a of said back casing section 10 12. Said bracket has an angularly-related forwardly-extended side portion 18 which overlies the right hand side wall 12b of said back casing section as viewed in Fig. 2. Said side portion 18 is terminated flush with the 15 front edge of said side wall and thereat is provided with a front inturned flange 20 which lies parallel with the back portion 16 of said bracket. Said disconnecting switch includes a switch frame having left and right 20 hand parallel side plates 22, of which the right hand plate is shown in Figs. 2 and 3, which are provided with rear oppositely and outwardly reflexed flanges 24 by which they are secured removably to the back portion 16 25 of said bracket by means of screws 26. Said side plates are secured together in spaced relation at their upper ends by means of a horizontal insulating plate 28 and are fixed in spaced relation at their lower ends by 30 means of a vertical insulating plate 34 which is secured to front inwardly directed flanges thereof by means of screws 36. Said insulating plate 28 is provided on its bottom face with a plurality of spaced and fixed contact 35 members 38 which are adapted to cooperate with similar movable contact members 40 which are carried on the confronting top face of a horizontal insulating plate 42. Said movable insulating plate 42 is adapted to be 40 reciprocated vertically to move the contact members 40 into and out of engagement with the cooperating fixed contact members 38 by means of suitable operating mechanism which includes the horizontal operating shaft 45 44. Said operating shaft extends between and is journaled in the two side plates 22 and projects beyond the right hand side plate to provide a cylindrical handle attaching portion 45. Said mechanism is such that by a 50 substantially 90° rotation of said operating shaft 44 in opposite directions it effects the opening and closing movement of said movable contact members. An operating handle 46 is provided for opening and closing said 55 disconnecting switch manually. Said handle is shown most clearly in Fig. 7, and includes a horizontal tubular section 48 which is adapted to be removably received on the cylindrical end 45 of said operating shaft 44 and is held in position thereon by suitable means as a resilient wire clip 50 which passes removably through said handle section 48 and through said shaft whereby to pin the handle removably to the shaft. Said handle 60 65 is provided with an outstanding flattened

portion 52 which extends outwardly through an enlarged circular opening 54 in the side wall 18 of said bracket and projects beyond the side wall of the enclosing casing. Said portion 52 is reflexed at a point at right 70 angles just outside the casing wall to provide an operating arm 53 to the upper end of which a cylindrical button or knob 56 is secured. The disconnecting switch above outlined is more fully shown and described in 75 my Patent No. 1,845,518, granted Feb. 16, 1932. The above description will suffice for an understanding of the present invention.

In accordance with the present invention means are provided which prevents the cover 80 10 of the enclosing casing from being opened unless the disconnected switch B has first been opened, and the closing of the switch except when the cover is closed, whereby to prevent improper access to and operation of 85 both switches. Said means comprises interlocking mechanism that at certain times interconnects the cover and the shaft of the disconnecting switch. Said mechanism includes a hub which is carried by and is ro- 90 95 tatable in the extension 18 of the supporting bracket in concentric relation with the switch shaft 44 and operating handle; and is actuated by said handle. Said hub is comprised of cylindrical inner and outer flange plates 95 58 and 60 which are larger than the opening 54 in said bracket and which overlie said opening on opposite sides of said bracket, and an intermediate hub plate 62 which is journaled in said opening 54. Said plates 100 105 are permanently secured together in co-axial relation by means of rivets 64 and 65 and thus constitute a flanged hub which is held against axial displacement but is freely rotatable in the bracket 14. Said plates are provided with aligned axial passages 66 therethrough through which the horizontal portion 46 of the operating handle is extended, the passage in the outer plates preferably being somewhat elongated to accommodate the flattened portion 52 of the handle. Said outer plate 60 as shown most clearly in Fig. 4 is provided with a pair of spaced struck-out ears 68 which engage opposite sides of the operating arm 53 of the handle, thus to connect said 110 115 handle and said hub removably together for conjoint rotary movement.

The rivet 65 which secures the plates 58, 60 and 62 of the hub together is provided with an enlarged inner shoulder 70 which provides 120 a pivotal support for a vertical locking plate 72. Said locking plate, as shown most clearly in Fig. 6, is generally rectangular in shape and has at its lower end a horizontally-elongated slot 74 in which the shoulder 70 of the rivet 65 is loosely located, the head 76 holding the plate secured against detachment to the hub. Said locking plate 72, which is adapted to be vertically reciprocated by rotary movement of the hub in response to switch opening 125 130

and closing movements of said operating mechanism is provided with an upper offset portion 78 which lies closely alongside and is held in position by the forwardly extended portion 18 of said bracket, as shown most clearly in Fig. 2. Said offset portion is provided with an inverted L-shaped slot having the long vertical portion 80 and a shorter horizontal and rearwardly extended portion 82; and a pin 84 which is carried by and is rigid with the side portion 18 of said bracket is received loosely in said slot. The length of the vertical portion 80 of said slot is arranged to be commensurate with the stroke 10 of said locking plate as it is reciprocated between its extreme positions corresponding to the open and closed positions of the switch. The lower edge 83 of the horizontal portion of said slot constitutes a locking shoulder 15 hereinafter to be described. Said offset portion 78 is further provided with an open top marginal slot 79 in its front edge having a long rear abutment face 85 and a shorter front abutment face 86 which constitutes a locking shoulder. A pin 88 is carried by and projects inwardly from the side wall of the cover 10 in position to engage the front edge 20 of said locking plate and enter said marginal slot as will hereinafter be described to lock 25 the cover closed in the switch closed position of the mechanism. Means are provided which constantly biases said locking plate into its foremost position, as shown in Fig. 5, in which the pin 84 and the shoulder 70 of 30 rivet 65 are disposed in the rearmost portion of the slots 82 and 74 respectively. Said means includes a thrust arm 90 which is pivotally connected with said locking plate at 92 and which extends rearwardly thereof and 35 has a reduced rectangular end portion 93 which projects loosely through a rectangular slot 94 in the outstanding ear 96 of an angular clip which is secured to the inner face of the portion 18 of said bracket. A compression spring 98 is disposed on said reduced portion 93 and bears against the shoulder 100 formed by said reduced portion 93 and against said ear 96 whereby constantly to urge said arm and the locking plate forward 40 in the casing. 45 Means are provided to limit the movement of the operating mechanism in a switch opening and closing direction. Said means, as shown most clearly in Figs. 1 and 4, includes a pair of spaced stop members 102 located about the periphery of said opening 54 and which are secured as by riveting to the outer face of the portion 18 of said bracket just beyond the margin of the outer plate 60. Said stops 50 are provided with angularly outstanding ears 104 which are adapted to be engaged by a radially outstanding arm 106 which is carried by the outermost plate 60 of said hub. Said arm 106 and the ears 104 of said stops 55 are provided with aligned holes to receive the hasp of a padlock, not shown, so that the switch handle can be locked either in its closed or open position. The right hand side wall of the back casing portion 12 in the vicinity of the operating mechanism is provided with a cutaway portion 108 which is sufficiently large to permit the bracket 14 and its assembled operating mechanism to be moved horizontally into and out of position without interference from the casing. Said 60 bracket 14 is also provided with a horizontal rearwardly-extended notch 110 which is arranged to receive the cover pin or projection 65 therein when the cover 10 is closed.

A latch 112 is carried by the outer side wall of the back casing portion 12 and is provided with a forward offset portion 114 which overlies the side wall of the front cover 10. Said latch is provided with a vertical notch 116 in its lower face which engages an outstanding lip 118 of a bracket 120 carried by said cover. Said latch 112 and bracket 120 are provided with parallel outstanding ears 122 and 124 having aligned passages 126 therethrough to receive a padlock by which the cover can be locked in closed position if desired. 70

In the position of the mechanism shown in Fig. 1, the switch B is open and the locking plate 72 is in its lowermost position in which the pin 84 is disposed in the top of slot 80 and the cover pin 88 is above and free from interference with the locking shoulder 86. Said pin 88, however, is in engagement with the abutment face 85 and constitutes a fulcrum on which the plate 72 rests. The thrust arm 90 acts in a line which includes, or is slightly below, the pin 88 in this position of the locking plate and consequently the locking plate will be held in the position shown in Fig. 1, in which the pin 88 is disposed in the forward end of the horizontal portion 82 of the L-shaped slot and directly above the vertical portion 80 thereof, and the shoulder rivet 70 is disposed in the rearmost portion of slot 74. In this position it is possible to close the interrupter, after which, as shown in Fig. 4, the cover pin 88 is disposed behind the locking shoulder 86, thus to prevent opening the cover 10. 75

The locking mechanism is also arranged to lock the switch mechanism of disconnecting switch B in the open position whenever the cover is open and until the cover has again been closed. The position of the parts with the cover open, is shown most clearly in Fig. 5, in which the cover pin 88 has been removed from engagement with the abutment face 85 of the locking plate and the locking plate, under the influence of the thrust arm 90, has moved about the shoulder 70 which now constitutes its pivotal support into its foremost position in which the pin 84 is disposed at the rearmost end of the horizontal slot 82. In this position of the locking plate, 80

100

105

110

115

120

125

130

closing movement of the switch is prevented by engagement of the fixed pin 84 with the horizontal locking shoulder 83.

Thus it will be evident that with the cover 5 10 in closed position it is possible to open and close the disconnecting switch B, since the latch 112 maintains the cover closed against the spring pressure exerted against the pin 88 thereof by the thrust arm 90. If, 10 however, the latch 112 is elevated to release the cover, by the opening movement of the cover, the switch is locked in open position. The pressure of the spring 98 can be sufficient, upon release of the latch 112, to move 15 the locking plate to switch locking position and simultaneously to push open the cover. It will also be evident that when the cover is in closed position and the switch is closed that the cover is securely locked in closed position. Furthermore by the provision of a 20 locking plate which is positively operated into both its switch locking and cover locking positions greater security is afforded than has been possible with prior devices wherein 25 the locking plate was positively operated at most in one direction only.

The inturned flange 20 of bracket 14, which for clearness is broken away in Fig. 2, conceals and protects the locking plate 72 30 against careless or accidental operation by an operative to release the switch mechanism for closing movement when the cover is open.

Various changes in the construction and arrangement of the parts may be made without departing from the scope of the invention.

I claim:

1. In an enclosed electric switch, a switch casing provided with a movable cover, a 40 switch in said casing having a movable switch member, switch operating mechanism for said movable switch member, a reciprocable locking member, means associated with said switch operating mechanism for reciprocating said locking member in response to opening and closing movement of said switch, said locking member having a locking shoulder, a fixed abutment adapted in one position of said locking member to engage said shoulder and in another position to be free therefrom, means constantly biasing said locking member into engagement with said abutment, and a cooperating abutment carried by the cover arranged to engage said locking member in 50 the closed position of the cover and move said locking shoulder free from said abutment.

2. In combination, a switch casing having a movable cover, a switch in said casing having a movable switch element, a switch operating member for said movable switch element, a locking plate pivotally connected with said switch operating member having a locking shoulder, a fixed abutment for engaging 60 said locking shoulder to hold the switch oper-

ating member in a predetermined position, an abutment on the cover for engaging the locking plate in the final closing movement of the cover to shift said locking plate and throw the locking shoulder thereof free of 70 said fixed abutment.

3. In combination, an enclosing casing for an electric switch having a movable cover, a switch in said casing having a movable switch element, a switch operating handle connected with said movable switch element, a locking plate pivotally connected with said switch operating handle, said locking plate having a locking shoulder, a fixed abutment for engaging said locking shoulder to hold said switch operating handle in predetermined position, and an abutment constituting a part of said cover for engaging said locking plate in the final closing movement of the cover to shift said locking plate and throw the locking shoulder thereof free of said fixed abutment, whereby to permit the closing movement of said switch operating handle.

4. In combination, a switch enclosing casing having a movable cover, a bracket secured removably in said casing, a switch mounted on said bracket having a switch operating element, a switch operating handle operatively connected with said switch element, means carried by said bracket having an operative connection with said switch operating handle arranged to lock said switch operating handle in switch open position, said means including a reciprocable locking plate having a locking shoulder, a stop carried by said bracket arranged in one position of said plate to engage said shoulder, means to bias said locking plate into the aforesaid locking position, and means associated with said cover for engaging said locking plate in the final closing movement of said cover to move said locking plate against its bias and throw the locking shoulder thereof free of said fixed stop, whereby to permit closing movement of the switch.

5. In combination, a switch enclosing casing having a movable cover, a bracket removably located in said casing, a switch mounted on said bracket having a switch operating shaft, an operating handle operatively connected with said shaft, means carried by said bracket for locking said operating handle in the switch open position thereof, said means including a reciprocable locking plate having an operative connection with said handle, said locking plate having a locking shoulder, a stop member carried by said bracket in position to engage said shoulder in the open position of the switch, means biasing said plate into engagement with said stop member, and means operative in response to the final closing movement of the cover to engage said locking plate and throw the locking shoulder thereof free of said stop.

6. In combination, a switch enclosing casing having a movable cover, a switch in the casing, operating mechanism for the switch, a reciprocable locking plate operated by said mechanism having a locking shoulder, an abutment arranged in one position of said plate to engage said shoulder to hold said operating mechanism in predetermined position, means constantly biasing said plate into locking engagement with said abutment, and means operative during the final closing movement of the cover to shift said plate against said bias and move said locking shoulder free of said abutment, whereby to permit the operation of said switch operating mechanism.

7. In combination, a switch enclosing casing having a hinged cover, a removable switch frame mounted in the casing, a switch supported by said frame including stationary and movable contact members, operating mechanism for the switch, a reciprocable locking plate carried by said frame and having a positive operative connection with said operating mechanism, said locking plate having a horizontal locking shoulder and a vertical locking shoulder, an abutment carried by said frame for engaging said horizontal locking shoulder in the switch open position of said locking plate, a second abutment carried by the cover arranged to engage said vertical locking shoulder in the switch closed position of said plate, means constantly biasing said locking plate into position to engage said first abutment member when said cover is open, said second abutment member arranged in the closed position of said cover to engage and move said locking plate against its bias into the position wherein said horizontal locking shoulder is free from said first abutment.

8. An electric switch mechanism comprising an enclosing casing having an opening thereinto, a door for closing said opening, a switch in said casing including stationary and movable contact members, operating mechanism for said movable contact member, an operating handle, a locking plate operatively connected with said mechanism to move between switch open and closed positions, said locking plate having a locking shoulder, a fixed abutment for engaging said locking shoulder, means to bias said locking plate into a position to engage said abutment, and means connected with said door having a part extended into position to engage said locking plate in the final closing movement thereof to move said locking shoulder free from said abutment, whereby to permit switch closing movement of said operating handle.

9. An electric switch mechanism comprising an enclosing casing having an opening thereinto, a door for closing said opening, a switch in said casing including stationary

and movable contact members, operating mechanism for said movable contact member, an operating handle, a locking plate operatively connected with said mechanism to move between switch open and closed positions, said locking plate having a locking shoulder, a fixed abutment for engaging said locking shoulder, means to bias said locking plate into a position to engage said abutment, and means connected with said door having a part extended into position to engage said locking plate in the final closing movement thereof to move said locking shoulder free from said abutment, whereby to permit switch closing movement of said operating handle, said locking plate also having a second locking shoulder for engaging the extended part of said door in the switch closed position of said plate whereby to prevent opening movement of said door.

10. An electric switch mechanism comprising an enclosing casing having an opening, a removable cover for said opening, a switch in said casing, switch operating mechanism including an operating handle located externally of said casing, a reciprocable locking plate having a pivotal connection with said switch operating mechanism and adapted to be operated positively between two positions corresponding to the switch closed and switch open positions of said mechanism, said plate having a slot therein, a fixed stop member adapted to enter said slot in the switch open position of said plate, means which constantly biases said plate in a direction to engage said stop, and means responsive to closing movement of said cover which moves said plate against its bias to disengage said stop, whereby to liberate said operating mechanism for switch closing movement.

11. An electric switch mechanism comprising an enclosing casing having an opening, a removable cover for said opening, a switch in said casing having switch operating mechanism including an operating handle which is located outside said casing, a vertically reciprocable locking plate having a pivotal connection with said mechanism, said locking plate having a slot therein comprising a vertical portion and a rearwardly extended horizontal portion, a fixed locking pin disposed in said slot, means constantly biasing said plate towards the front of said casing whereby to bring said locking pin in the horizontal portion of said slot, and means carried by the cover arranged to move said plate against its bias and bring said locking pin in the vertical portion of said slot.

12. An electric switch mechanism comprising an enclosing casing having an opening, a removable cover for said opening, a switch in said casing having switch operating mechanism including an operating handle which is located outside said casing, a vertically re-

ciprocable locking plate having a pivotal connection with said mechanism, said locking plate having therein an inverted L-shaped slot comprising a vertical portion and a horizontal portion, a fixed pin disposed in said L-shaped slot, means biasing said locking plate for forward movement in the casing, whereby to permit said pin to occupy the horizontal portion of said slot in the switch

10 open position of said plate, a second pin carried by said cover which engages said locking plate in the closing movement of said cover and urges it against its bias whereby to bring said first pin into the vertical portion of said slot, said locking plate also having a second open top vertical slot, the open top of which is disposed beneath said cover pin in the closed position of said cover.

13. An electric switch mechanism comprising an enclosing casing having an opening, a removable cover for said opening, a switch in said casing having switch operating mechanism including an operating handle which is located outside said casing, a vertically reciprocable locking plate having an inverted L-shaped slot comprising a vertical portion and a rearwardly extended horizontal portion, a fixed locking pin disposed in said slot, means biasing said locking plate forwardly in the casing whereby to bring said pin in the horizontal portion of said slot in the lowermost position of said plate, a second pin carried by said cover arranged to engage said plate during the closing movement of the cover, whereby to move said plate against its bias and bring said locking pin in the vertical portion of said slot, said locking plate also having a second vertical open top slot therein, the open top of which is disposed beneath said cover pin in the closed position of said cover, and means operatively connecting said locking plate with said switch operating mechanism arranged to raise and lower said plate positively in response to switch closing and opening movements of said mechanism.

14. In combination an enclosing casing having an opening, a removable cover for said opening, a remote controlled electrically operated circuit interrupter in said casing, a manually controlled disconnecting switch electrically in series with said interrupter also contained in said casing, both said interrupter and switch being accessible only through said opening, operating mechanism for said disconnecting switch including an operating handle located externally of said casing, and means interlocking said cover and the operating mechanism of said disconnecting switch arranged to lock said cover against opening movement except in the open position of said mechanism and also when said cover is open to lock said mechanism against closing movement, said means including a vertically reciprocable locking plate which is

operatively connected with and is moved positively in both directions by said operating mechanism between an upper and a lower position which correspond to the open and closed positions of said switch, and fixed stops carried by said casing and cover, said plate having notches which receive said stops and lock the cover against removal when the switch is closed and also lock said mechanism open when the cover is removed.

15. An enclosed electric switch comprising an enclosing casing having an entrance and a door for said entrance, an electric switch in said casing having switch operating mechanism, and locking mechanism for said door and operating mechanism including a locking plate movable in opposite directions following corresponding movements of said operating mechanism having means engaging said plate with a fixed part of said casing when the switch is open, whereby to hold the switch from closing, said plate also being engaged by said door and held thereby out of such engagement when the door is closed, and said plate also having means which is engaged with a part of said closed door when the switch is closed and which holds the door against opening.

16. An enclosed electric switch comprising an enclosing casing having a door, an electric switch in said casing having switch operating mechanism, and locking mechanism for said door and switch operating mechanism including a hub rotatable in opposite directions following corresponding movements of said operating mechanism, and a locking plate loosely connected with and reciprocated by said hub, said plate having means which is engaged with a fixed part of said casing only when the switch and also the door is open and which locks said switch mechanism against movement from a switch open position, and said locking plate also having means which is engaged by a part of the closed door and which is held by said part out of holding relation with said switch mechanism, and which plate also has means which engages said door and holds it in closed position when said switch mechanism is in switch closed position.

17. An enclosed electric switch comprising an enclosing casing having a door, an electric switch in said casing having operating mechanism including an operating shaft, a hub surrounding and having a driving connection with said shaft, and interlocking mechanism between said operating mechanism, door and casing including a locking plate loosely connected with and reciprocable with said hub having a locking engagement with said door when it is closed and the switch is closed and which releases said door only when the switch is open, and which also has a locking engagement with a part of said casing only when the switch and also the

cover is open and which holds the operating mechanism against closing movement, said plate having means which is engaged by the closed door and which then holds said plate 5 away from such locking engagement.

18. An enclosed electric switch as defined in claim 17 wherein said casing has means which provides a rotatable support for said hub independently of said shaft, and said 10 shaft being loosely extended through said hub and having a removable driving connection therewith.

19. An enclosed electric switch as defined in claim 17 wherein said casing has means 15 independent of said shaft in which said hub is rotatable, said shaft having an operating handle that has a detachable driving connection with said hub.

20. An enclosed electric switch as defined 20 in claim 17 wherein said casing has means independent of said shaft in which said hub is rotatable, said hub having an abutment that extends through an opening of said casing, and said casing having a pair of spaced 25 abutments that are alternately engaged by said hub-abutment.

21. An enclosed electric switch comprising an enclosing casing having an entrance, a cover for said entrance, an electric switch in 30 said casing having a supporting plate that overlies a side wall of said casing and has a ledge that faces the entrance of said casing, a hub journalled in said plate behind said ledge, a locking plate loosely connected with 35 said hub and lying between it and said ledge, means which urges said plate toward said ledge, switch operating mechanism including an operating shaft which is concentric and has a driving connection with said hub, 40 said plate having means which engages a fixed part of said supporting plate when said door and said switch are open and which holds said switch mechanism locked against closing movement, and said plate also having 45 means which engages a part of the closed door and holds it against opening when said switch mechanism is in switch closed position.

22. An enclosed electric switch comprising an enclosing casing having an entrance, a 50 door closing said entrance, an electric switch in said casing having a supporting bracket that has an extension that overlies a side wall of said casing, a hub rotatable in said extension, switch operating mechanism, said extension having a pair of abutments extended through an opening in said side wall, and said hub having an abutment that alternately engages said extension-abutments, and an operating handle located mainly externally 55 of said casing and having a driving connection with said operating mechanism and also with said hub.

In testimony whereof, I have signed my name to this specification.

65 HENRY P. PINKHAM.
